Primary Examiner — Jennifer L Rempfer*(74) Attorney, Agent, or Firm* — Koffsky Schwalb LLC; Mark I. Koffsky(57) **CLAIM**

We claim the ornamental design for a mattress, as shown and described.

DESCRIPTION

FIG. 1 is a front perspective view of a mattress in accordance with the present invention;

FIG. 2 is a top view thereof;

FIG. 3 is a bottom view thereof;

FIG. 4 is a left view thereof;

FIG. 5 is a right view thereof;

FIG. 6 is a front view thereof; and,

FIG. 7 is a rear view thereof.

The dashed lines in the figures form a part of the claimed design.
